(57) **CLAIM**

The ornamental design for a dental implant ridge gauge, as shown and described.

DESCRIPTION

FIG. 1 is a right side elevational view of the dental implant ridge gauge showing my new design therefor with portions shown in broken line forming no part of the design throughout the drawings;

FIG. 2 is a left side elevational view thereof;

FIG. 3 is a top plan view thereof;

FIG. 4 is bottom plan view thereof;

FIG. 5 is a front elevational view thereof;

FIG. 6 is a rear elevational view thereof;

FIG. 7 is front perspective view thereof;

FIG. 8 is a rear perspective view thereof;

FIG. 9 is a right side elevational view of a second embodiment of the dental implant ridge gauge showing my new design therefor with portions shown in broken line forming no part of the design throughout the drawings;

FIG. 10 is a left side elevational view thereof;

FIG. 11 is a top plan view thereof;

FIG. 12 is bottom plan view thereof;

FIG. 13 is a front elevational view thereof;

FIG. 14 is a rear elevational view thereof;

FIG. 15 is front perspective view thereof; and,

FIG. 16 is a rear perspective view thereof.
